United States Patent Office.

LEWIS J. SCHAEFER, OF PHILADELPHIA, PENNSYLVANIA.

Letters Patent No. 76,252, dated March 31, 1868.

IMPROVED CURTAIN-FIXTURE.

The Schedule referred to in these Letters Patent and making part of the same.

TO ALL WHOM IT MAY CONCERN:

Be it known that I, LEWIS J. SCHAEFER, of the city of Philadelphia, and State of Pennsylvania, have invented a new and improved Curtain-Fixture; and I do hereby declare that the following is a full, clear, and exact description of the same, reference being had to the accompanying drawing, and to the letters of reference marked thereon, making part of this specification, in which—

Figure 1 is a front view, and

Figure 2 is a side view.

Similar letters refer to similar parts in the two views.

A is a cage or frame, which is rectangular in shape, and open behind. B'B' are extensions or jamb-plates at the back of the cage, and are the means whereby the frame or cage is fixed to the jamb of a window or other suitable place. C is a vertical rod, which takes, through an opening in the top of the cage, into the recess or hollow formed by its ends and sides. D is a spiral spring on the said rod C. Its ends are contained between the upper end of the cage and the projections on the end of the rod. The projections α α' are two helical feathers, fixed on opposite parts of the surface of the cylindrical axis or rod C, and which work in the spiral channel of the spring D in the same manner that a carpenter's screw works in a piece of wood.

The rod C is inserted into the spring by entering the helical feathers in the spiral groove or opening of the spring, and, turning the rod in the proper direction, it screws or works down until the feathers gain the end of the spring, and the cord-hook E, on the upper end of the rod, faces in the required direction. By the application of the helical feathers to the rod, the spring D is more securely fixed to it, and the rod is made adjustable in the direction of its length, for, by turning it continually in one direction or the other, it rises or lowers, through the medium of the helical feathers taking into the groove of the spring.

To adjust the cord-roller to the fixture, the rod C must be raised, by pressure applied to the hook E, until the spiral spring acquires expanding force sufficient to keep the shade from lowering by its own weight, attention also being given to the degree of tension of the cord, to keep it from abrading on the hook D.

What I claim as my invention, and desire to secure by Letters Patent, is—

The combination of the rod C with its projections α α' , or their equivalent, and the spring D, so arranged that the adjustment of the fixture is effected by turning the said projections between the coils of the spring, substantially as herein specified.

In testimony whereof, I hereunto sign my name to this specification in presence of two subscribing witnesses.

LEWIS J. SCHAEFER.
